BACKFIRE RELEASE

Daniel L. Wertz, Elmira, N. Y., assignor to Eclipse
Machine Company, Elmira, N. Y., a corpora-
tion of New York

Application January 28, 1932, Serial No. 589,517

8 Claims. (Cl. 290—37)

This invention relates to a backfire release for automatic starting mechanism and more particularly to a device for preventing actuation of an automatic starting mechanism during backward rotation of the engine to be started.

Automatic starting mechanisms have heretofore been constructed embodying various devices for preventing actuation of the starting mechanism when the engine is running and causing actuation thereof when the engine stops; but these devices have generally been inoperative to prevent actuation of the starting motor when the engine is rotating backward as in case of a backfire. It will be readily appreciated that the operation of the starting mechanism under such circumstances throws heavy stresses on the starting elements which it would be desirable to avoid.

It is an object of the present invention to provide a novel device for rendering an automatic starting mechanism inoperative to start an engine during backward rotation thereof.

It is another object to provide such a device which is arranged to prevent reoperation of the automatic starting mechanism after a backfire, until the operator has again placed the automatic starting mechanism in active condition.

A further object is to provide such a device in which the control elements of the automatic starting mechanism are operated in consequence of backward rotation of the engine to render the automatic starting mechanism inoperative.

Another object is to provide such a device which may be made as an attachment to an automatic starting mechanism without expensive alteration thereof.

Further objects and advantages will be apparent to those skilled in this art from the following description taken in connection with the accompanying drawing in which:

Fig. 1 is a semi-diagrammatic illustration of one preferred embodiment of the invention, the parts being shown in their normal idle position;

Fig. 2 is a similar view of a second embodiment of the invention; and

Fig. 3 is a detail partly in section of a third embodiment of the invention.

Referring first to Fig. 1 of the drawing, there is illustrated an electrical system for an internal combustion engine, not shown, comprising a battery 1, grounded at 2, and connected by a lead 3 to a magnetically operated starting switch 4. Switch 4 is connected by leads 5 and 6 to a starting motor SM which is grounded at 7 to complete the starting circuit.

The starting switch is operated by a solenoid 8 which is energized by a control circuit including battery 1, leads 3 and 4', manual switch 5', leads 6' and 7', stationary contact 9 and movable contact 10 which is mounted on a spring strip 11 grounded, as indicated at 12. Manual switch 5' may, if desired, be arranged to control the ignition system of the engine as indicated on the drawing.

Means are provided for opening contacts 9, 10 when the engine starts in order to deenergize the solenoid 8 and allow the starting switch 4 to open. As here illustrated, this means comprises a lever 13 pivoted at 14 and actuated by a solenoid plunger 15 to engage the end of the spring strip 11 and move contact 10 away from contact 9. Plunger 15 is actuated by two coils 16 and 17. Coil 16 is connected by a lead 18 to the dead side of the starting switch 4 and is grounded at 19; and coil 17 is connected to an engine-driven generator G by a lead 21, and is also grounded at 19. The function of the coil 16 is to move the lever 13 to open contacts 9, 10 when the engine starts, and the function of coil 17 is to retain said contacts open as long as the engine is in operation.

According to the present invention, independent means are provided for opening the contacts 9, 10 responsive to backward rotation of the engine and for holding said contacts open under the control of the operator. As here illustrated, this means comprises a slidable magnetic plunger 22 which is arranged to operate a lever 23, the free end of which lever carries a pin 31. Pin 31 is adapted to engage and bend 35 back the spring strip 11, carrying the movable contact 10 away from fixed contact 9, upon actuation of the plunger 22. Plunger 22 is actuated by a coil 24 connected at one end by a lead 25 to the lead 6' of the control circuit, and connected at the other end by a lead 26 to the plunger 22. Plunger 22 is insulated from its bearing elements as indicated at 28, and lever 23 is insulated as indicated at 29 whereby the circuit of the magnet 24 is normally open. Initial motion of the plunger 22, however, causes the pin 31 to engage the spring strip 11, which completes the circuit of coil 24 to the ground 12 whereby said coil is energized to further actuate the plunger 22 and retain the contact 10 in its open position until the circuit of the magnet 24 is broken at the manual switch 5'.

Initial actuation of the plunger 22 in response to the backward rotation of the engine is effected, as illustrated, by means of a pressure-

responsive element such as a flexible diaphragm 32 mounted within a chamber formed by a casting element 33. This chamber is connected by means of a conduit 34 with an element of the fuel intake system of the engine such as the intake manifold indicated at 35. Plunger 22 is fixed at one end to the center of diaphragm 32, while insulated therefrom as indicated at 27. Pressure in the intake manifold will thus cause the diaphragm 32 to move said plunger to engage the pin 31 with the spring strip 11 and complete the ground connection for coil 24.

In the operation of the device, starting with the parts in the positions illustrated in Fig. 1 closure of the manual switch 5' closes the control circuit, causing energization of the solenoid 8 and consequent closure of the starting switch 4, whereby the starting motor is energized to crank the engine. When the engine starts, the plunger 15 is actuated by the coil 16 to open contacts 9, 10, and the generator coil 17 retains said contacts open as long as the engine is in operation.

Should the engine backfire, however, the generator is inoperative to energize the coil 17, and the contacts 9, 10 would automatically be allowed to close. However, backward rotation of the engine causes pressure to be built up in the intake manifold 35, which pressure is transmitted through the conduit 34 to the chamber 33 and causes the diaphragm 32 to move the plunger 22 sufficiently to cause the pin 31 on lever 23 to engage the spring strip 11. The consequent energization of coil 24 causes the plunger 22 to bend back the spring strip 11, opening contacts 9, 10 and retaining the same in open position.

When backward rotation of the engine has ceased, the operator need only open the manual switch 5' to deenergize the coil 24, whereupon reclosure of the starting switch causes the starting operation to be repeated in the usual manner.

In the embodiment of the invention illustrated in Fig. 2 the elements of the starting system and of the automatic starting mechanism are the same as illustrated in Fig. 1 and are similarly numbered, but a somewhat different arrangement with respect to the backfire releasing mechanism is provided. As here illustrated, a diaphragm 36 which is subjected to pressure in the fuel intake system in the same manner as the diaphragm 32, is arranged to operate a lever 37. Lever 37 is fulcrumed at 38 and is pivoted at its free end 39 to a link 41. Link 41 is provided with a shoulder 42 arranged to engage the spring strip 11 and thereby move contact 10 out of engagement with contact 9.

In order to retain the contacts 9, 10 open, link 41 is provided with retaining means here shown in the form of a magnetic latch 43 arranged to engage in a notch 44 in said link. Latch 43 is normally retained in its disengaged position by means of a spring 45 but is adapted to be moved into engagement with the link 41 by means of a coil 46, one end of which is adapted to be connected by a lead 47 to the lead 6' of the control circuit, and the other of which is connected to a brush 48. Initial movement of the link 41 causes a conducting section 49 thereof to engage the brush 48 and a grounding brush 50 whereby the circuit of coil 46 is completed. When the notch 44 is moved into registry with latch 43, the latch will therefore engage therein and retain contacts 9, 10 open until the magnetic circuit is broken by opening of the manual switch 5'.

The operation of this embodiment of the invention is substantially similar to that previously described except that the opening of the contacts 9, 10 is effected directly by the force of the intake pressure on the diaphragm 36, and the latch 43 and coil 46 merely serve as retaining means to prevent reactuation of the starting mechanism until the manual switch 5' has been opened and reclosed.

In the embodiment illustrated in Fig. 3, the diaphragm 51 which corresponds to diaphragm 32 in Fig. 1 is provided with a grounding contact 52 which is normally adjacent a contact 53 mounted on one end of a magnet core 54 but insulated therefrom as indicated at 55. Core 54 is arranged to be energized by a coil 56, one end of which is connected to contact 53 by a lead 57. The opposite end of coil 56 is connected by a lead 58 to the manual switch 5' in the same manner as coils 24 and 46 in the previous embodiments of the invention. Contacts 52 and 53 are formed of magnetic material whereby magnetization of core 54 by coil 56 causes contact 52 to be held up against contact 53 on the end of the core 54, thus maintaining the ground connection for the coil 56 whereby said coil remains energized after the intake pressure has been withdrawn from the diaphragm 51 until the manual switch 5' has been opened to break the circuit of coil 56.

The opposite end of core 54 extends within a short distance of the upper end of spring strip 11 on which is mounted a weight member 59 of magnetic material. Energization of coil 56 causes said weight member to be drawn over 35 against the end of core 54, thus opening contacts 9, 10 and preventing closure of the starting switch.

In the operation of this embodiment of the invention, backward rotation of the engine causes pressure in the intake system which causes diaphragm 51 to move contact 52 into engagement with contact 53, thus completing the ground connection for coil 56. If the ignition switch 5' is closed at this time, the coil 56 is energized, thereby opening contacts 9, 10 and preventing actuation of the starting mechanism until the ignition switch 5' is opened and reclosed.

It will be understood that since the spring strip 11 will vibrate upon release thereof after deflection, a time delay will be introduced thereby which will prevent the effective energization of the control circuit for a predetermined time after such release. Such time delay is desirable in order to permit the engine to come to rest, since backfiring may under certain circumstances continue until the ignition switch is opened, and if the ignition switch were immediately reclosed, actuation of the starting mechanism might take place while the engine was still rotating backward if it were not for this time delay.

Although certain embodiments of the invention have been shown and described in detail, it will be understood that various other embodiments are possible and various changes may be made in the construction and arrangements of the elements without departing from the spirit of the invention as defined in the claims appended hereto.

What is claimed is:

1. In combination with an engine to be started having a fuel intake system, automatic starting mechanism including a magnetic starting switch, a control circuit therefor including a pair of contacts, means responsive to forward rotation of

the engine for opening said contacts, and means for opening said contacts responsive to positive pressure in said fuel intake system due to backward rotation of the engine.

2. In combination with an engine to be started having a fuel intake system, automatic starting mechanism therefor including a magnetic starting switch, a control circuit therefor including a manual switch and a pair of contacts, means responsive to forward rotation of the engine for opening said contacts, means for opening said contacts responsive to positive pressure in said fuel intake system due to backward rotation of the engine, and means under the control of said 10 manual switch for holding said contacts open.

3. In combination with an engine to be started, having a fuel intake system, automatic starting mechanism therefor including a magnetic starting switch, a control circuit therefor including a 20 pair of contacts, means responsive to forward rotation of the engine for opening said contacts, a pressure-responsive element, means connecting said element to the fuel intake system of the engine whereby variations in pressure therein 25 will move said element, and means whereby motion of said element responsive to positive pressure in said system causes said contacts to be opened.

4. In combination with an engine to be started having a fuel intake system, automatic starting mechanism therefor including a magnetic starting switch, a control circuit therefor including a pair of contacts, means responsive to forward rotation of the engine for opening said contacts, a pressure-responsive element, means connecting said element to the fuel intake system of the engine whereby variations in pressure therein will move said element, means whereby motion 30 of said element responsive to positive pressure in said system causes said contacts to be opened, and manually controlled means energized by such motion for holding said contacts open.

5. In combination with an engine to be started having a fuel intake system, automatic starting mechanism therefor including a magnetic starting switch, a control circuit therefor including a manual switch and a pair of contacts, means responsive to forward rotation of the engine for 45 opening said contacts, a pressure-responsive element, means connecting said element to the fuel intake system of the engine whereby variations in pressure therein will move said element, means 50

whereby motion of said element responsive to positive pressure in said system causes said contacts to be opened, and a holding circuit for said contacts including said manual switch and a solenoid, said solenoid acting to supplement the 5 action of the pressure-responsive element in opening and holding open said contacts.

6. In combination with an engine to be started having a fuel intake system, automatic starting mechanism therefor including a magnetic starting switch, a control circuit therefor including a manual switch and a pair of contacts, means responsive to forward rotation of the engine for opening said contacts, a pressure-responsive element, means connecting said element to the fuel 10 intake system of the engine whereby variations in pressure therein will move said element, means whereby motion of said element responsive to positive pressure in said system causes said contacts to be opened, a holding circuit for said 15 contacts including said manual switch and a solenoid, said solenoid acting to supplement the action of the pressure-responsive element in opening and holding open said contacts, and means responsive to initial movement of the pressure-responsive member to close said holding circuit. 20 25

7. In combination with an engine to be started having a fuel intake system, automatic starting mechanism for the engine including a magnetic 30 starting switch, a control circuit therefor including a set of contacts, an element movable by positive pressure above atmospheric, in the fuel intake system, means connecting said element with one of said contacts whereby said motion of 35 the element is transmitted thereto to open said contacts, and means for delaying effective closure of said contacts for a predetermined time after the dissipation of said positive pressure in the intake system. 40

8. In combination with an engine to be started having a fuel intake system, automatic starting mechanism for the engine including a magnetic starting switch, a control circuit therefor including a set of contacts, an element movable by 45 positive pressure above atmospheric, in the fuel intake system, means connecting said element with one of said contacts whereby said motion of the element is transmitted thereto to open said contacts, and means for vibrating said contact for a predetermined time after release thereof. 50
